UNITED STATES PATENT OFFICE

JEAN D. SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

APPARATUS FOR TREATING HYDROCARBONS

Application filed March 15, 1929. Serial No. 347,832.

The invention relates to the production of lower boiling point hydrocarbons from heavier hydrocarbons by treatment of the latter at temperatures within the cracking range.

5 It is my belief that a cracking reaction is divided into two steps, a primary reaction where the largest portion of the gasoline-like or light distillates is produced with accompanying formation of heavier liquid products; and a secondary reaction, where said heavier liquid products are converted mostly into sludge-like and coke-like products with little attendant increase in the formation of light distillates.

15 As a feature of the invention, I therefore propose to subject hydrocarbon oil to conditions of conversion, and to remove the heavier liquid products from the reaction or separating zone before secondary reaction has proceeded to the extent of forming objectionable quantities of coke and sludge-like constituents.

Regulation of the rate of withdrawal of the liquid products may be obtained by observing the proportion of sludge and coke-like products contained in the liquid products withdrawn from the reaction or separating zone, and so controlling the rate of withdrawal that a definite limit of proportion of coke and sludge-like constituents is not exceeded, as shown by any analytical method, such as benzol centrifuge. The limit should be below 5% and preferably below 2%. Experience has indicated that, when the limit is not exceeded, comparatively little coke formation occurs in the process.

The degree of secondary reaction taking place in the heavier liquid products is controlled mainly by the rate of withdrawal thereof, and, therefore, by the size or volume of the pool of unvaporized oil maintained in the reaction or separating zone at high temperature. The sizes of reaction or separating zones now in use commercially, and which have diameters of 5 to 10 feet, make it necessary to maintain, particularly when treating heavy oils, a very shallow pool having a small cubical content. Such practice sometimes renders the control of the operation difficult for the operator, as a small

increase in height of the pool means a comparatively large increase in the time during which the heavier liquid products of primary reaction remain in the reaction or separating zone subjected to high temperature.

55 As a feature of the invention, I propose to design the lower part of vertical reaction or separating chambers now in use in a manner proper to facilitate control of the withdrawal of the heavy liquid products of primary reaction.

To this end the part of the reaction or separating drum wherein the liquid products of reaction collect before their withdrawal, takes preferably the shape of an elongated conduit of small diameter relative to the main portion of the drum, for instance 2 feet or less, or it may take a conical shape of restricted area, or such other shape as will permit the residue contained therein to have 70 a relatively large height in relation to its horizontal cross section. In this manner, relatively small variations of volume correspond to relatively great variations in height.

75 Other features of the invention will be apparent from the following description and from the attached drawing, where the single figure is a diagrammatic view partly in section, partly in elevation, of an apparatus suitable to carry out the invention.

80 While I have illustrated an application of the principle of the invention to a particular type of oil conversion process, and to a particular design of reaction chamber, it is to be understood that the invention may be used in any type of process wherein oil is raised to a conversion temperature and in other types of apparatus used therefor.

85 Referring to the drawing, oil may be charged from line 1, through pump 2 to and through heating coil 3 located in suitable furnace setting 4. The oil is heated while passing through coil 3 to a cracking temperature and is discharged through transfer line 5 and valve 6 into chamber 7, in which separation of vapors from heavier liquid products of reaction takes place. The vapors may be removed from chamber 7 through line 8 and valve 9, passing into dephlegmator 10, where- 100

in fractionation may be effected, assisted if necessary by an additional cooling medium, such as raw oil or distillate injected through lines 11 and valves 12 in the usual manner.

5 Vapors remaining uncondensed after passing through dephlegmator 10 pass out the top thereof through line 13 and valve 14, then through condenser 15; liquid condensate and uncondensable gases pass into receiver 16, provided with usual gas and distillate valve-controlled draw-offs 17 and 18.

Reflux condensate formed in dephlegmator 10 may be withdrawn from the bottom thereof through line 19, having valve 20, and returned to the charging line 1 in the usual manner through lines and hot oil pump (not shown) or removed totally or partly from the system.

20 Temperatures, rate of feed and pressures in heating coil 3 and chamber 7 are so regulated that the heavier liquid products separated in and withdrawn from chamber 7 do not contain sludge-like or coke-like material in excess of the predetermined limit, as 25 heretofore described.

As a feature of the invention, the vertical chamber 7, which is usually provided with bottom manhole throat 21, may be further provided with a vertical conical extension 30 reservoir 22 connected with throat 21, and having its apex at the bottom. The pool of unvaporized oil is preferably maintained with its surface or level within the conical reservoir, such as indicated at A, and usual 35 liquid level indicating devices are provided, such as temperature recorders or level try cocks, as shown at 23 and 24.

The liquid products of reaction are preferably removed through the apex of the reservoir, through lowermost line 25 having valve 26—additional side draw-off lines 27 having valves 28 may be provided in case of emergency.

40 While I have shown a conical reservoir 22, a cylindrical reservoir having small diameter relative to chamber 7 may be used, but I have found that a conical reservoir possesses additional advantages over other forms. For instance, the tendency of the unvaporized oil 45 to become converted beyond the limit prescribed, and the tendency of solid or semi-solid material to deposit at the bottom of the reservoir are offset by the progressively increasing turbulence of the stream of unvaporized material as it reaches zones of progressively decreasing diameter during its passage 50 through conical reservoir 22, until it is removed through lower draw-off 25.

60 The invention may be applied to processes where separation of vapors from unvaporized products takes place in a chamber or chambers under approximately the same temperatures and pressures as are obtained at the discharge of the heating coil, or under reduced temperature and/or pressure, with or

without accompanying reaction, and where digestion or soaking zones may be interposed between the heating coil and the separating chamber.

As an illustration of the operation according to the invention, the conversion of an oil having a gravity of about 20 Bé. at a temperature of about 900-920° F. and a pressure of about 170 pounds on the heating coil and chamber, produced a yield of about 30% of 75 437° F. end point gasoline, with a yield of about 55% of cracked residuum having a gravity of about 10 Bé., containing 1% of B. S. This was accompanied with formation of coke in the process to the extent of 80 less than five one-thousandths (0.005) of one pound per barrel of oil treated.

I claim as my invention:

In a combination with an enlarged vapor separating chamber of an oil cracking system having a cylindrical bottom manhole throat extending downwardly therefrom and of materially smaller diameter than said chamber, of an inverted conically-shaped elongated residual draw-off means conforming in its largest diameter to the diameter of said throat and in registration with the bottom of said throat, and an outlet pipe connected to the apex of said inverted conically-shaped draw-off means.

In testimony whereof I affix my signature.
JEAN D. SEGUY.
